UNITED STATES PATENT OFFICE.

HANS MUNSCH, OF BERLIN, GERMANY.

DESIGN FOR A LOUD-SPEAKER CASING.

Application filed May 31, 1927. Serial No. 22,235. Term of patent 3½ years.

To all whom it may concern:

Be it known that I, HANS MUNSCH, a citizen of the German Republic, residing at Berlin, Germany, have invented a new, original, and ornamental Design for Loud-Speaker Casings, of which the following is a specification, reference being had to the accompanying drawing, forming part thereof.

Figure 1 of the drawing is a front elevation of a loud speaker casing, showing my new design, and Fig. 2 is a diagrammatic side elevation.

I claim:

The ornamental design for a loud speaker casing, as shown.

HANS MUNSCH.
